UNITED STATES PATENT OFFICE

141,217

DESIGN FOR A NIGHT LATCH OR SIMILAR ARTICLE

Charles H. Nehls, Detroit, Mich., assignor to Independent Lock Company, Fitchburg, Mass., a corporation of Massachusetts

Application December 26, 1944, Serial No. 117,086

Term of patent 14 years

(Cl. D50—5)

To all whom it may concern:

Be it known that I, Charles H. Nehls, a citizen of the United States and a resident of Detroit, in the county of Wayne and State of Michigan, have invented a new, original, and ornamental Design for Night Latch or Similar Article, of which the following is a specification, reference being had to the accompanying drawing, forming a part thereof.

I claim:

The ornamental design for night latch or similar article, as shown.

CHARLES H. NEHLS.
